The ornamental design for a hockey stick, as shown and described.

DESCRIPTION

FIG. 1 is a front elevational view of a hockey stick in accordance with a first embodiment of my new design.

FIG. 2 is a first side elevational view of the design of FIG. 1.

FIG. 3 is a second side elevational view of the design of FIG. 1, opposite the first side.

FIG. 4 is a rear elevational view of the design of FIG. 1.

FIG. 5 is a top plan view of the design of FIG. 1.

FIG. 6 is a bottom plan view of the design of FIG. 1.

FIG. 7 is a front elevational view of a hockey stick in accordance with a second embodiment of my new design.

FIG. 8 is a first side elevational view of the design of FIG. 7.

FIG. 9 is a second side elevational view of the design of FIG. 7, opposite the first side.

FIG. 10 is a rear elevational view of the design of FIG. 7.

FIG. 11 is a top plan view of the design of FIG. 7; and, FIG. 12 is a bottom plan view of the design of FIG. 7.
